WARP KNITTING MACHINE

Fred Charles Sorton, Whitinsville, Mass., assignor
to Whitin Machine Works, Whitinsville, Mass.,
a corporation of Massachusetts

Application April 13, 1948, Serial No. 20,723

8 Claims. (Cl. 66—86)

1

This invention relates to warp knitting machines.

In warp knitting machines as heretofore constructed the threading of the guide bars is a somewhat difficult operation. The present invention provides an arrangement whereby the guide bars can be threaded more readily than heretofore.

Speaking generally, this is accomplished by, as it were, hinging the guide bars to the brackets or swing hubs, so-called, by which the guide bars are connected to their rock shafts. This permits the guide bars to be swung to positions in which the guides are accessible for rethreading. Preferably the hinging is at the slide brackets that are interposed between the guide bars and the rock shaft swing hubs. Provision may be made for locking the hinged guide bars in normal operation positions, i. e. in their knitting positions with respect to their rock shafts, and for interlocking the guide bars with the source of power by which the knitting machine is driven so that a guide bar can be swung to its threading position only when the machine is inoperative. A holder may also be provided to hold the guide bar in a threading position. In the case of knitting machines having two or more guide bars, one in front of the other, both may be hinged to swing in the same direction to threading positions. With such arrangements it is sufficient to interlock only the outer guide bar with the source of power of the knitting machine directly, inasmuch as this hinging arrangement requires that the inner guide bar or guide bars be in knitting position when the outer guide bar is in knitting position, and hence one interlocking connection will serve for all the guide bars.

The foregoing is illustrated in the accompanying drawings which show the preferred form of the invention. In those drawings Fig. 1 is a rather sketchy perspective view of a warp knitting machine of conventional form to which my invention has been applied. Fig. 2 is a larger view at two of the slide brackets supporting the inner and outer guide bars of the machine of Fig. 1. Fig. 3 is a vertical cross-section of the pertinent parts of the machine adjacent two such slide brackets, the guide bars being shown in knitting positions relative to their mountings. Fig. 4 is a front elevation at one of the slide brackets of the outer guide bar. Fig. 5 is a rear elevation of one of the slide brackets of the inner guide bar. Fig. 6 is a vertical section generally similar to that of Fig. 3 but showing the guide bars in threading position and also showing the

2

interlock between the hinged guide bars and the control mechanism of the machine. Fig. 7 is a detail of the blocks of the interlocking mechanism.

In general the machine illustrated in the drawings comprises a supporting frame consisting of a number of vertical members 1 and horizontal members, some of which are shown at 2, rigidly coupling the verticals 1 together, two parallel yarn beams, one of which is shown at 3, for carrying the warp threads on spools 4 (shown empty in the drawing), yarn tensioning devices, a part of one of which is shown at 5, a guide bar rock shaft 6, reciprocatable guide bars 7 and 8 mounted on the rock shaft 6 and carrying the thin yarn guides indicated at 7a and 8a which wrap the yarns around the needles, a needle bar 9 carrying the needles (which are bearded needles), a sinker bar 10 carrying the sinkers which operate between adjacent needles, a presser 11 serving the various needles, a cloth beam 12 to receive the cloth from the needles, two pattern wheels 13 and 14 for shifting the guide bars 7 and 8 longitudinally in accordance with a predetermined pattern, links 15 connecting the guide bars 7 and 8 to the pattern wheels respectively, and mechanism, for the most part not shown, for rocking the guide bar rock shaft 6 and for actuating the needle bar, sinker bar, presser and cloth roll in manners that will be understood from prior practices with machines of the kind illustrated. The machine is power driven by power supplied through a master switch located at, say, 16 and opened and closed by longitudinal movement of a controller or control bar 17 extending across the front of the machine, Fig. 1, and provided with a number of conveniently reached handles 18 by which the operator can shift the control bar 17 to the right to open the master switch to stop the machine or place it out of operation, or shift the bar to the left (position shown in Fig. 1) to close the switch 16 to operate the machine to knit cloth. The control bar is carried in a number of brackets 19 fastened to the framework of the machine. One of the warp threads guided by the guides of guide bar 7 is indicated at 20; one of those of guide bar 8 is indicated at 21.

Inasmuch as warp knitting machines and their operation are well-known, it is not necessary to describe the operation of the machine as so far described.

Somewhat as heretofore the outer guide bar 7 is carried by a number of slide brackets 22 mounted on a similar number of brackets or

swing hubs 26, so-called, which are mounted non-rotatably and non-slidably on the rock shaft 6. Similarly the inner guide bar 8 is carried by a number of slide brackets 28 mounted on a similar number of swing hubs 29, likewise non-rotatably and non-slidably mounted on the rock shaft 6. In accordance with the present invention however the upper slide bar 30 of each bracket 25 is cylindrical, and is carried, and also is both slidable and rotatable, in a bearing 31 projecting from a plate 32 carried by the adjacent swing hub 26. Each bearing 31 is held to its plate 32 by bolts 33 which pass through vertical slots 34 in the plate 32; the slots are to permit the bearing to be adjusted vertically along their plates 32 somewhat. A projection 35 rigidly mounted on the respective plate 32, carries a threaded bolt 36 which is screwed into the bearing member 31 of the plate and positions the bearing, or helps the bolts 33 to position it, along the plate. The purpose of this is to provide for adjusting the guides 1a vertically with respect to the needles; that is to say, by turning the bolts 36 one way or the other the bearing members 31 can be raised or lowered, and thereby the guide bar 7 raised and lowered carrying its guides 1a with it. Each bolt 36 may be provided with a set nut below its projection 35 as illustrated. As customary, a second slide bar 37 is provided on each slide frame 25. Guide members 38 on the swing hubs 26 provide upwardly open slide ways for the slide bars 37.

Each plate 32 is slotted vertically at each of its two (upper and lower) ends as indicated at 43 and 44, Figs. 3 and 4, a block 45 is provided to span each of these slots, and bolts 46 pass through these blocks and slots and are threaded into the respective swing hub 26. These serve to hold the plates 32 to the swing hubs 26 while permitting them to slide vertically on the hub faces as will be understood. The slots 43 and 44 are made long enough to permit each plate to slide from a position where its slide bar 37 is well within its slide way provided by the member 38, Figs. 3 and 4, to a position where the slide bar is well above the member 38. Latches in the form of sliding bolts 47 set in the swing hubs serve to releasably lock the slide plates 32 in their low positions in which their slide bars 37 are within the slide ways of the guide members 38; the outer end of each of these bolts is tapered to enter a tapered seat 48 in its plate 32, Figs. 3 and 6, and each is urged toward its locking or latching position, Fig. 3, by a spring 49 back of it.

The low positions of the plates 32 and guide bar 7, i. e. their positions in Fig. 3, are their operative or knitting positions, or rather are their operative or knitting positions with respect to, say, the rock shaft 6. While the machine is operating to knit fabric therefore, it will be observed, the slide brackets 25 with their slide bars 30 and 37 permit the guide bar 7 to be reciprocated right and left by the pattern mechanism, e. g. wheel 17, in quite the same manner as the slide brackets employed heretofore. In addition however the cylindrical slide bars 30 and their bearings 31 constitute hinges for the guide bar 7, the axes of which are in line with each other and substantially parallel to the axis of the rock shaft 6. During the knitting operations, and accordingly while the bars 37 are within the slide ways of the guide members 38, these guide members hold the bars 37 to the swing hubs 26 and thus prevent swinging on the hinges at 30-31. When the machine is at rest however, i. e. while the

knitting operations are discontinued, the latches 47 can be released and the plates 32 raised safely, along the faces of the swing hubs 26, until the slide bars 37 are lifted completely free of the 5 guide members 38. The guide bar 7 having first been freed of its pattern links 19, may then be 10 swung on the hinges 30-31 toward one side of the machine and to a position whereat the guides 1a are conveniently accessible for threading; for 15 example, it may be swung to substantially a horizontal position as shown in Fig. 6. The bar 7 may be held in such a threading position, while being threaded, by, say, a holder in the form of a hook or hooks 56 hooked to one or more of 20 the slide bars 37 and to some conveniently located bar or shaft 56a of the machine. After threading is completed the guide bar 7 can be restored to its operating or knitting relation of course by again swinging it down until its slide bars 37 25 come to the slide ways of the guide members 38, and then lowering the plates 32 to engage these bars in these slide ways. The pattern link or links 19 may then be restored to the guide bar, and the latches 47 again allowed to enter their keeper recesses 48.

Obviously the plates 32 and their latches 47, whatever form they may have, can be operated in the foregoing manner in various ways, and either separately or as a unit. Preferably however 30 I interlock them with the control bar or controller 14 as before indicated, and preferably I do this in the manner shown in the drawings. That is to say, a rock shaft 50 is provided extending substantially the full length of the machine; 35 it may be mounted in, say, the swing hubs 26, or in separate brackets fixed firmly to the rock shaft 6 so as to shift therewith. At each swing hub 26 the rock shaft 50 is provided with a member 51 firmly affixed to the rock shaft 50 so as 40 to rock therewith. Each of these members 51 has an arm engaging with the adjacent bolt 47 in such a manner as to be able to withdraw the respective bolt 47 from its seat 48 in the adjacent plate 32 as indicated at 52, Figs. 3 and 6, 45 and a projecting finger 53 extending into a slot 54 of the adjacent plate 32. When the shaft 50 is rocked in such a manner as to withdraw the bolts 47 from the various slide plates 32, the projecting fingers 53 serve to raise the slide plates 50 32, as shown in Fig. 6, to thereby withdraw the guide bars 37 from their notches in the guide members 38. The fingers 53 may have enough play in the slots 54 to permit the bolts 47 to be 55 fully retracted from their keepers or recesses 48 before the fingers begin to raise the plates 32, as will be understood from Figs. 3 and 6. One or more arms 56 are affixed to the rock shaft 50 to rock it. Each of these arms is provided with a pin 59 riding in a slot 60 in an adjacent arm 61 mounted on, but swinging freely with respect to, the guide bar rock shaft 6, and which is hinged to a connecting rod 62. The opposite end of this connecting rod is hinged at 63 to one end of a 60 bell crank lever, or one corner of a triangular plate 64, which is hinged at 65 to one of the vertical frame members 1 of the machine; the other end, or third corner, of 64 is hinged by a connecting rod 66 to an arm 67 fixed to the controller or control shaft 14. The two bars 62 and 66 may be adjustable in length as indicated by the screw threads on them, in order to be readily adapted to the operation desired. Also the connections of the connecting rod 66 to 67 and 64 are loose so as to permit the sliding 65 70 75 of the control shaft before mentioned, or the

arm or arms 67 may be mounted slidably on the control bar 14 but keyed to the bar so as to rock with it. An elongated block 70, partly encircling the control bar 14 and attached to this bar at some convenient place, and a second elongated block 71, also partly encircling the control bar but affixed to the frame of the machine to the left of and adjacent the block 70, Figs. 1 and 7, complete the interlocking mechanism. Fig. 7 shows the relative positions of these two blocks when the master switch 13 is open so that the machine is at rest and the guide bar 7 is in its knitting position, Fig. 3.

It will be observed that the foregoing mechanism, from the rock shaft 50 to the controller 14, permits the operator to actuate the slide plates 32 and their latches 47 by rotating the controller or control bar 14. The full line position of this mechanism in Fig. 6 is its position when the latches 47 are withdrawn and the slide plates 32 are raised, so that the guide bar 7 can be turned to and occupy its threading position, Fig. 6. The blocks 70 and 71 are so disposed that with the mechanism in this position, the block 70 is displaced angularly somewhat from its position in Fig. 7, so that the adjacent ends of 70 and 71 face each other at least partially. As a result, the control bar 14 cannot be moved to the left to close the master switch 13 to start the machine in operation while the slide plates 32 are raised. However, when the threading of the bar 7 has been completed and this bar turned down on its hinges 30—31 as before described, the operator can rotate the controller or control bar 14, say by grasping whichever handle 15 may be most convenient to him at the moment, and thereby shift the interlock or interlocking mechanism to its dotted line position in Fig. 6. This permits the slide plates 32 to move downward to confine the guide bar 7 to its operation relation to its rock shaft 6, Fig. 3, as before described; and permits the bolts 47 to return to their latching positions, Fig. 3. Also this turning of the bar 14 brings the block 70 to its position in Fig. 7. As a result the control bar can now be shifted longitudinally to the left to close the switch 13 to bring the machine into operation. When this is done however, block 70 is carried to beside block 71, Fig. 1, so that as long as the machine continues in operation the guide bar 7 must remain in its operating or knitting position with respect to the rock shaft 6, and only by first stopping the machine can it again be turned to its threading position.

The inner guide bar 8, which guides such threads as 21, also is hinged, and in quite a similar manner, so that it can be swung in the same direction as the guide bar 7, and toward the same side of the machine, to a position where its guides also are accessible for threading, Fig. 6. I. e., to this end each of its swing hubs 29 is provided with a bearing 76 which is fastened to the back of the lower end of the hub by a bolt or bolts 77. Conveniently these bolts 77 can be passed through vertical slots 78 in the bearing members so that the height of the guide bar 8, and accordingly the guides 8a, can be adjusted at these bolts 77 with respect to the needles. The lower slide bar 79 of each slide bracket 28 of the inner guide bar 8 is made cylindrical, and both slidable and rotatable in its respective bearing 76. The upper slide bar 80 of each guide bar bracket 28 is held to the face of its respective swing hub 29 normally, i. e. during knitting, by a plate 81 which rests on a spacer

block 82 and in cooperation with the face of the hub provides a slide-way for the slide bar 80 during knitting. Each plate may be held to the spacer block by a single bolt 83.

As in the case of the slide brackets 25 therefore, the slide brackets 28 provide for the reciprocation of the guide bar 8 by the pattern, e. g. 18, during knitting, and in addition provide for hinging of their guide bar. The plates 81 have the same function as the guide members 38, that is to say they confine their slide brackets to the swing hubs during the knitting operations. In addition in the present instance the plates 81, or their bolts 83, also perform the functions of the sliding bolts 47, in that they constitute latches by which the guide bar 8 is released for swinging. I. e. by loosening the bolts 83 the plates 81 may be swung, Fig. 5, so as to uncover their respective slide bars 80. This permits the respective slide brackets 28 to rotate in their bearings 76 and thereby the inner guide bar 8 to swing to a convenient threading position, Fig. 6. By the reverse operations the guide bar 8 can be restored of course to its knitting position relative to its hinges 76, 79 and its rock shaft 6.

It will be observed from the foregoing that in arrangements where two or more guide bars are employed and all are arranged to swing in the same direction, it is not necessary to interlock the inner bars directly with the control of the machine. Since in such cases the inner bar or bars, for example 8, must be restored to its or their knitting position or positions relative to the other parts of the machine before the outer guide bar such as 7 can be restored to its knitting relations, and similarly the inner guide bars cannot be placed in threading positions unless the outer bar has been placed in its threading position previously, a single interlocking mechanism for the outer guide bar serves as an interlock for all guide bars that may be mounted behind it as well.

It will be understood that my invention is not limited to the details of construction and operation illustrated and described above except as appears hereafter in the claims, and that the claims are intended to include equivalents of the various elements mentioned in them.

I claim:

1. In a warp knitting machine having knitting mechanism including needles, yarn guides to feed yarns to said needles, a guide bar on which said yarn guides are mounted, and a rock shaft carrying said guide bar, characterized by the fact that said guide bar is hinged to the rock shaft on an axis substantially parallel to the axis of the rock shaft, for swinging movement to a threading position remote from the needles, and a holder is provided to hold said guide bar in said remote threading position.
2. In a warp knitting machine having knitting mechanism including needles, yarn guides to feed yarns to said needles, a guide bar on which said guides are mounted, a rock shaft, swing hubs on said shaft, and slide brackets to which said guide bar is attached, characterized by the fact that said slide brackets are hinged to said swing hubs on axes parallel to the axis of said shaft, for swinging movement of said guides to a threading position remote from the needles, and a holder is provided to hold said guide bar in said remote threading position.
3. The subject matter of claim 2, each of said swing hubs and its associated slide bracket hav-

ing, slidably related, one a slide bar and the other a bearing for the respective slide bar, characterized by the fact that said slide bars and bearings therefor constitute the hinges by which the guide bar is hinged to the swing hubs, for swinging movement of said guides to a threading position remote from the needles, and a holder is provided to hold said guide bar in said remote threading position.

4. In a warp knitting machine having knitting mechanism including needles, yarn guides to feed yarns to said needles, a guide bar on which said yarn guides are mounted, and a rock shaft carrying said guide bar, characterized by the fact that said guide bar is hinged to the rock shaft on an axis substantially parallel to the axis of the rock shaft, and a releasable latch is provided to lock the guide bar to the rock shaft in knitting relation thereto, release of the latch permitting the guide bar to be swung on its hinges, to move said guides to a threading position remote from the needles, and a holder is provided to hold said guide bar in said remote threading position.

5. In a warp knitting machine having knitting mechanism including needles, yarn guides to feed yarns to said needles, a guide bar on which said yarn guides are mounted, and a rock shaft carrying said guide bar, and a controller to start and stop the machine, characterized by the fact that said guide bar is hinged to the rock shaft on an axis substantially parallel to the axis of the rock shaft, and an interlock is provided between said guide bar and controller to prevent hinged movement of said guide bar to a non-knitting position when the controller is in machine-operating position.

6. In a warp knitting machine having knitting mechanism including needles, yarn guides to feed yarns to said needles, a guide bar on which said yarn guides are mounted, and a rock shaft carrying said guide bar, and a controller movable to start and stop the machine, characterized by the fact that said guide bar is hinged to the rock shaft on an axis substantially parallel to the axis of the rock shaft, a latch is provided to lock said guide bar in knitting relation to the rock shaft, a connection is provided through which said controller can actuate said latch, a block on said controller, and a second block mounted apart from the shaft, said two blocks being so disposed relatively as to block movement of the controller to latch-releasing position while in machine-starting position and block move-

ment of the controller to machine-starting position when in latch-releasing position.

7. In a warp knitting machine having knitting mechanism including needles, yarn guides to feed yarns to said needles, at least two guide bars on which said guides are mounted, and at least one rock shaft carrying said guide bars, characterized by the fact that each of said guide bars is hinged to the rock shaft that carries it

10 on an axis substantially parallel to the axis of the rock shaft, and both are movable around their respective hinge axes from their knitting positions, relative to the respective hinge axes, toward the same side of the machine, to move 15 said guides to a threading position remote from the needles, and a holder is provided to hold said guide bars in said remote threading position.

8. In a warp knitting machine having knitting mechanism including needles, yarn guides to 20 feed yarns to said needles, at least two guide bars on which said guides are mounted, at least one rock shaft carrying said guide bars, and a controller movable to start and stop the machine, characterized by the fact that each of said guide

25 bars is hinged to the rock bar that carries it on an axis that is substantially parallel to the axis of the rock bar, one of said bars is movable around its hinge axis from its knitting position relative to its said axis toward the adjacent side

30 of the machine, a second of said guide bars is movable around its own hinge axis from its knitting position relative to its said axis toward the other of said guide bars, and an interlock between said controller and the first mentioned of 35 said two guide bars to prevent said first mentioned bar being moved from its said knitting position when the controller is in machine-operating position.
